[21] Appl. No.: 43,735

CLAIM

[22] Filed: Apr. 29, 1987

The ornamental design for a combined shelf and adjustable support arm for attachment to a table, as shown and described.

[52] U.S. Cl. D6/418; D6/511

DESCRIPTION

[58] Field of Search D6/491, 396, 509-511,
D6/418; 248/122, 145, 281.1

FIG. 1 is a side elevational view of a combined shelf and adjustable support arm for attachment to a table, the opposite side being a mirror image thereof, showing my new design;

FIG. 2 is a top plan view;

FIG. 3 is a bottom plan view;

FIG. 4 is a rear elevational view; and

FIG. 5 is a front elevational view thereof.
